UNITED STATES PATENT OFFICE.

WILLIAM H. CRANE, OF POUGHKEEPSIE, NEW YORK, ASSIGNOR TO MOLINE PLOW COMPANY, A CORPORATION OF ILLINOIS.

BUTT-ADJUSTER MECHANISM FOR GRAIN-BINDERS.

1,270,016.

Specification of Letters Patent. Patented June 18, 1918.

Application filed June 1, 1916. Serial No. 101,108.

To all whom it may concern:

Be it known that I, WILLIAM H. CRANE, a citizen of the United States, residing at Poughkeepsie, in the county of Dutchess and

5 State of New York, have invented certain new and useful Improvements in Butt-Adjuster Mechanism for Grain-Binders, of which the following is a specification, reference being had therein to the accompanying drawing.

10 My invention relates to improvements in grain binding machines, and has reference more particularly to the butt adjuster mechanism which operates on the butts of the grain to assist in delivering the grain to the packers and to square up the butts and hold them square while the bundle is being tied.

15 There are in common use two forms of butt adjusters, one a vibratory adjuster, and 20 consisting usually of a board supported in an upright position on the binder deck and vibrated by suitable mechanism so as to act on the butts of the grain; and the other a rotary or traveling adjuster, which consists 25 of an endless traveling conveyer apron supported in upright position on the binder deck and driven by suitable means so that the apron will travel against the grain butts. The vibratory form of butt adjuster is that 30 most commonly employed, but there are certain territories where the traveling form of adjuster is demanded, and in such territories there are seasons when the condition of the grain requires the use also of a vibratory 35 adjuster.

The object of my invention is to meet these 40 different conditions encountered in practice and to provide for the use in the same machine of the two different forms of adjusters at will, so that a machine equipped with one form of adjuster may be conveniently and quickly changed to employ the other form of adjuster and vice versa.

With this end in view my invention consists in a form and construction of the machine frame which will permit either form 45 of butt adjuster to be removably mounted therein at will, in combination with a butt adjuster driving element common to both 50 forms of adjusters, and intermediate driving members for transmitting motion from the common driving element to the different forms of adjusters, said intermediate driving members being preferably detachable

from and attachable at will to the driving 55 element, according to the particular form of butt adjuster which for the time being is to be employed.

My invention consists also in the details of construction and combination of parts 60 hereinafter described and claimed.

In the accompanying drawings:

Figure 1 is a side elevation of the upper portion of the binding deck and elevator of a grain binder having my invention embodied therein, and illustrating the machine equipped with a vibratory butt adjuster.

Fig. 2 is a similar view of the parts shown in Fig. 1 but with a rotary or traveling butt adjuster substituted.

Fig. 3 is a sectional elevation on an enlarged scale through the upper roll of the traveling adjuster and the driving mechanism therefor, the section being taken on the line a—a of Fig. 2.

Fig. 4 is a horizontal sectional plan view on the line b—b of Fig. 3.

Referring to the drawings:

Referring to Figs. 1 and 2 which illustrate only such portions of the machine as 80 will be necessary for an understanding of my invention, 1 indicates the binding deck of the machine and 2 the upper end of the elevator by which the cut grain is conveyed from the grain receiving platform (not 85 shown) upwardly and delivered onto the binding deck, these parts being suitably sustained by the machine frame 3, a fragment only of which is illustrated. In Fig. 1 the machine is shown as equipped with a vibratory butt adjuster 4, while in Fig. 2 the machine is equipped with a traveling butt adjuster 5, these two forms of adjusters being detachably mounted in place on the grain 90 deck so that they may be interchanged at 95 will and one substituted for the other as occasion demands.

6 indicates a butt adjuster driving shaft which extends along the outer side of the elevator frame at the rear side of the same 100 and which shaft receives its motion through the medium of a bevel gear 10 fixed to the shaft, with which gear 10 meshes a bevel gear on the upper roll of the lower elevator, the said roll receiving its drive from 105 a suitable source of power, usually from the ground wheels of the machine in the advance of the same through the field. Near its up-

per end this shaft is supported for rotation in a lower laterally projecting bracket 7 on an upright plate 8 fixed to the side of the elevator frame, and in an upper laterally 5 projecting bracket 9 on the upper end of said plate, the upper end of the shaft being extended upwardly beyond the bracket as shown more particularly in Fig. 3. The hub of the bevel gear 10 is extended upwardly 10 and formed with a spur pinion 11 by means of which the driving motion of the driving shaft is imparted to the traveling butt adjuster when the latter is applied, as will be more fully described hereinafter.

15 The upper projecting end of the driving shaft is adapted to receive a driving crank 12 through which the motion of the driving shaft is transmitted to the vibratory butt adjuster when the latter is applied to the 20 machine, this driving crank being detachably connected with the shaft, as by a fastening pin 12^a engaged with the crank and shaft, so that the crank may be removed therefrom when the traveling form of butt adjuster is 25 substituted.

On reference to Fig. 1 which shows the machine equipped with the vibratory form of butt adjuster, the driving crank 12 is shown applied to the driving shaft and operatively connected with the vibratory board 4^a of the adjuster by means of a connecting arm 13 fixed at one end to said board and having at its opposite end a depending journal 14 seated loosely in a bearing opening 30 in the end of the crank, the arm thus acting as a driving connection between the crank and board, and acting to sustain the board in an upright position on the binder deck, the rotation of the crank acting to impart 35 to the board its usual vibratory motions against the butts of the grain. The board 4^a is given support at its lower end by means of a crank arm 15 provided at one end with a crank 15^a which is mounted loosely in 40 alined openings in the upper bracket plate 9 and the lower bracket plate 8 respectively, the opposite end of the crank arm being provided with a vertically extending crank 15^b having pivoted to it a sleeve 16 in which is 45 slidingly supported a slide 17 fixed to the side of the adjuster board. The coöperation of the slide with the sleeve 16 acts to support the lower end of the board while at the same time it permits of a relative motion 50 between the board and crank arm in the vibratory action of the former. Connected with the crank 15^b is an upright shield 18 constituting in effect an extension of the butt adjuster board. A shifter bar 19 has its 55 lower end detachably connected by means of fastening bolts 19^a with an arm 20 fixed to and extending upwardly from the side of the extension 18, which shifter bar extends upwardly to the upper end of the elevator frame 2 where it is provided with a number

of notches 21 adapted to be engaged with a tooth 22 on the elevator frame, the extremity of the shifter bar being formed with a handle 23 by means of which it may be adjusted or shifted endwise. In the endwise 70 shifting of the shifter bar, the extension 18 will be likewise shifted and a corresponding motion will be imparted to the board 4^a by means of the connection of said board with the crank 15^b through the medium of the 75 slide 17 on the board and the sleeve 16 on the crank arm; whereby the butt adjuster board may be adjusted to different positions transversely of the binder deck, or in other words in the direction of the length of the 80 grain thereon.

When the traveling form of butt adjuster is to be substituted for the vibratory adjuster, the adjuster bar 19 is disconnected from the arm on the extension 18, the driving crank 12 is detached from the driving shaft 6, and the board 4^a and attached parts are removed bodily from the binder deck. The traveling butt adjuster is then applied to the deck so that it will occupy the position shown in Fig. 2.

This traveling adjuster comprises upper and lower frame members having upper and lower lateral fixed studs 24 and 25 projecting therefrom at the upper end of the adjuster, a driving shaft 26 being mounted for rotation in said studs and having fixed to it a roll 27. The shaft extends at its lower end downwardly and beyond the end of the stud 25 and is provided with screw threads on 100 which is screwed a driving pinion 28 which may be unscrewed therefrom and detached at will for the purpose presently to be described. There is a corresponding idler shaft 26^a and idler roll 27^a at the opposite 105 end of the adjuster as indicated by dotted lines in Fig. 2, and around the two rolls passes an endless apron 29 provided as usual with conveyer cleats, which apron is given a traveling motion by the rotation of the 110 shaft 26.

To adapt a butt adjuster of this form to be applied to the machine and to be driven from the common drive shaft 6, the upper bracket 9 before alluded to is formed with 115 an opening 30 which receives the lower stud 25 when the adjuster is set in position. Adjacent this opening the bracket is provided with a second opening 31 in which is removably seated a bolt 32 extending downwardly from the bracket. The bolt is surrounded by a sleeve or bushing 33 which is clamped fixedly to the bolt by means of a nut 34 screwed on the lower end of the bolt, the sleeve thus forming a journal on which 120 a transmitting pinion 35 is loosely mounted and is detachably confined by the said nut. This pinion when thus applied will mesh with and be driven by the pinion 11 before alluded to, and will engage and drive the 125

*

130

pinion 28 on the lower end of the shaft 26 and thus impart motion to the traveling apron.

In applying the traveling form of adjuster after the removal of the vibratory device, the transmitting pinion 35 having been previously mounted on its journal on the bracket 9, the traveling adjuster, after first removing the pinion 28 from shaft 26, is seated over the binder deck and the stud 25 is passed through the opening 30 in the bracket 9. Pinion 28 is then engaged with the transmitting pinion and applied to the threaded end of shaft 26, and while held in this position, the shaft is rotated by turning the rolls and apron, the effect of which will be to screw the pinion on the shaft. A bracket arm 36 containing a bearing opening therein, is applied to the upper end of the elevator frame 2 and the bearing opening passed over the upper stud 24 of the butt adjuster and the arm confined detachably in place by means of the bolts 37 passing therethrough and into the elevator frame. The lower end of a shifter bar 19 is then fastened by means of the bolts 19^a before alluded to, to an arm 38 depending from a bracket plate 39 fixed to the upper frame bar of the adjuster device, whereby connection is made between the shifter bar and the butt adjuster for shifting the latter and adjusting it to different positions transversely of the binder deck. The parts are now in such operative relations that the rotation of the driving shaft 6 will through the medium of the train of gearing consisting of the pinion 11, transmitting gear 35 and pinion 28, rotate the roll 29 and impart to the apron a traveling motion.

In changing back again to the vibratory form of adjuster, the shifter bar 19 is disconnected, the bracket 36 removed, the pinion 28 unscrewed, the transmitting pinion being either removed or left in place, and the adjuster device lifted bodily from the deck. The other form of butt adjuster is then set in position over the binder deck, the crank 15^a of the crank arm inserted in the bearing openings in the two brackets, and the driving crank 19 applied to the upper end of the driving shaft, the parts being thus in such operative relations that the rotation of the driving shaft will impart to the vibratory board its vibratory motion.

As a result of the construction described, the change from one form of butt adjuster to another may be conveniently and quickly effected, there being but few parts to be detached or changed when one form of the device is removed and the other form substituted.

A farmer, therefore, by being furnished with the two forms of butt adjusters and their respective associated parts, is enabled to use in the same machine either form of

adjuster according to the conditions encountered. The change from one form to the other may be speedily made and with little inconvenience.

A further advantage of the interchangeability of the parts is the convenience and economy in the shop in the manufacture of the parts, the entire machine frame and the primary driving devices being the same for both kinds of adjusters, the only change necessary being in respect to the removable crank shaft for driving the vibratory adjuster, and the pinions by which the rotary adjuster is driven from the drive shaft.

Having thus described my invention, what I claim is:

1. In a grain binder, the combination of a frame, a butt adjuster supported thereby and replaceable at will by a butt adjuster of different type, a driving shaft, and operative connections between the shaft and the first mentioned butt adjuster, said connections being formed to be broken to permit the removal of the first mentioned butt adjuster, and means whereby the driving shaft may be operatively connected with a butt adjuster of different type when the latter is substituted for the other.

2. In a grain binder, the combination of a frame, a traveling butt adjuster supported thereby and replaceable at will by a vibratory butt adjuster, a butt adjuster driving shaft, operative connections between the said shaft and the traveling butt adjuster, said connections being formed to be broken to permit the removal of the traveling butt adjuster, and means whereby said shaft may be operatively connected to a vibratory butt adjuster when the latter is substituted for the other.

3. In a grain binder, the combination of a frame constructed to support interchangeably either a vibratory butt adjuster or a traveling butt adjuster, and a driving member mounted in the frame and having provision for operative connection alternately with either form of butt adjuster according to the particular one for the time being in use.

4. In a grain binder, the combination of a frame, a butt adjuster supported thereby and replaceable at will by a butt adjuster of a different type, a butt adjuster driving member mounted in the frame and operatively connected with the first mentioned butt adjuster to operate the same, and means for operatively connecting said driving member with the second mentioned butt adjuster when the latter is substituted for the other.

5. In a grain binder, the combination of a frame, a traveling butt adjuster supported thereby and replaceable at will by a vibratory butt adjuster, a butt adjuster driving member mounted in the frame and opera-

- 4
5. In a grain binder, the combination of a frame, an arm detachably connected with the frame and provided with a bearing, a traveling butt adjuster sustained by the frame and having its upper roll journaled in said arm, said traveling butt adjuster being replaceable at will by a vibratory butt adjuster, a butt adjuster driving member mounted in the frame and operatively connected with said roll for operating the same, and means for operatively connecting the driving member with the vibratory butt adjuster when the latter is substituted for the other. 40
6. In a grain binder, the combination of a frame, a vibratory butt adjuster supported thereby and replaceable at will by a traveling butt adjuster, a butt adjuster driving shaft mounted in the frame, a crank on said shaft operatively connected with the vibratory butt adjuster for operating it, and a pinion on the shaft in position to be operatively connected with the traveling butt adjuster when the latter is substituted for the other. 45
7. In a grain binder, the combination of a frame, a traveling butt adjuster supported thereby and replaceable at will by a vibratory butt adjuster, a butt adjuster driving shaft mounted in the frame, a pinion on said shaft geared to the traveling butt adjuster to operate the same, and means for operatively connecting the driving shaft with the vibratory butt adjuster when the latter is substituted for the other. 50
8. In a grain binder, the combination of a frame, a vibratory butt adjuster supported thereby and replaceable at will by a traveling butt adjuster, a butt adjuster driving shaft mounted in the frame, a crank shaft detachably connected with the driving shaft and operatively connected with the vibratory butt adjuster, and a pinion on said shaft in position to be operatively geared with a traveling butt adjuster when the latter is substituted for the other. 55
9. In a grain binder, the combination of a frame, an arm detachably connected with the frame and provided with a bearing, a traveling butt adjuster sustained by the frame and having its upper roll journaled in said arm, said traveling butt adjuster being replaceable at will by a vibratory butt adjuster, a butt adjuster driving member mounted in the frame and operatively connected with said roll for operating the same, and means for operatively connecting the driving member with the vibratory butt adjuster when the latter is substituted for the other. 60
10. In a grain binder, the combination of a frame constructed to support interchangeably either a vibratory butt adjuster or a traveling butt adjuster at will, and a butt adjuster shifting device sustained by the frame and constructed to be detachably connected alternately to either form of butt adjuster according to the particular one for the time being in use to shift the same. 65
11. In a grain binder, the combination of a frame, a vibratory butt adjuster supported thereby and replaceable at will by a traveling butt adjuster, and a butt adjuster shifting device sustained by the frame and detachably connected with the vibratory butt adjuster for shifting it, said device being attachable at will to a traveling butt adjuster when the latter is substituted for the other. 70

In testimony whereof, I have affixed my signature in presence of two witnesses.

WILLIAM H. CRANE.
